UNITED STATES PATENT OFFICE.

RUDOLPH SIMMS, OF WASHINGTON, DISTRICT OF COLUMBIA, ASSIGNOR
OF ONE-HALF TO BERNHARD FERDINAND SCHUBERT, OF WASHINGTON,
DISTRICT OF COLUMBIA.

FURNACE FOR CONSUMING SMOKE.

SPECIFICATION forming part of Letters Patent No. 740,323, dated September 29, 1903.

Application filed October 6, 1902. Serial No. 126,101. (No model.)

To all whom it may concern:

Be it known that I, RUDOLPH SIMMS, of Washington, District of Columbia, have invented certain new and useful Improvements 5 in Furnaces for Consuming Smoke; and I do declare the following to be a full, clear, and exact description of the invention, which will enable others skilled in the art to which it appertains to make and use the same.

10 The present invention has for its object to provide an improved furnace which is adapted to very effectually consume the particles of smoke in the gases of combustion, so that the fuel is utilized to the fullest advantage, 15 complete combustion obtained, and the escape of any smoke prevented.

The invention consists, essentially, in a furnace having an outlet-passage through which the products of combustion after having acted upon the boiler-flues and other heating-surfaces of the boiler flow to the chimney, a burner or burners in said passage, and means, such as baffles, dampers, or throttles, or other equivalent devices, for causing the 25 products of combustion to pass either into or out of contact with the flame of said burner. By this construction the gases of combustion may be permitted to pass directly into the stack or chimney when the fuel on the grate 30 is highly incandescent and the passage is free of any smoke, or when fresh coal is supplied to the grate and heavy smoke develops the gases of combustion may be compelled to come within the zone of action of the burner 35 or burners, so that they will be highly heated by the flames of the said burner or burners and consumed.

The invention also consists in certain combinations of parts, as will be hereinafter fully 40 described, and pointed out in the claims.

The figure of the drawing represents a vertical longitudinal section through a furnace embodying my invention.

From the hearth A of an ordinary boiler- 45 furnace the gases of combustion start and pass under a boiler B and along its sides to the rear end and then return through the flues of the boiler in the ordinary well-known manner. They ascend now in a pocket or 50 chamber C, the lower part of which is di-

vided into two chambers by a partition D and in the upper part of which two baffles, dampers, or throttles E and E' are arranged, which may be coupled together in any convenient manner, so as to take simultaneously 55 either a horizontal or a vertical position. In the drawing the throttles are shown in the horizontal position, and the gases of combustion are therefore compelled to pass out of the inner pocket-chamber beyond the partition D into the outer pocket-chamber adjacent to the front wall of the furnace in which a suitable number of burners F are arranged, getting a supply of crude oil from outside through a pipe G, which is connected with a 60 reservoir of crude oil and which is provided with a cut-off or valve H, serving to regulate the supply or to shut it off entirely. The flames of the burners F raise the temperature of the gases considerably, and all the particles 65 of smoke are consumed, thereby increasing the heat, so that the gases when they finally pass through between the open throttles E and E' escape into the flue K and chimney L completely free of smoke. The throttles E and E' 70 are shown in the figure to be secured to horizontal rods carrying each a small arm e and e', the ends of which are connected by a link. One or the other of the horizontal rods may have a suitable handle, and it will be understood that by turning the same and by bringing one of the throttles from the horizontal 75 into a vertical position the other throttle is compelled to follow and take also a vertical position, or vice versa. In such event the 80 gases of combustion ascend vertically from the inner pocket-chamber, which connects with the boiler-flues at the front end of the boiler, and then pass through a flue K over the boiler directly into the chimney L. The 85 vertical position is given to the throttle when the fire in the grate is so far advanced that no smoke develops; but as soon as the gases of combustion convey smoke in any considerable quantity the throttles E and E' are 90 turned into the position shown in the drawing, and the oil-valve H is opened so as to bring the gases in contact with the flames from the burners F, whereby the carbon of 95 the smoke is consumed.

Having thus fully described my invention, what I claim as new, and desire to secure by Letters Patent, is—

1. A furnace having an outlet-passage for the products of combustion, a burner in said passage, and means for causing the products of combustion to pass either into or out of contact with the flame of said burner.
2. A furnace having an outlet-passage for the products of combustion, a burner in said passage, and baffles (one or more) for varying said passage to cause the products of combustion to pass either into or out of contact with the flame of said burner.
3. A furnace having an outlet-passage for the products of combustion, a burner in said passage, a series of baffles for varying said passage to cause the products of combustion to pass either into or out of contact with the flame of said burner, and means for synchronously operating the baffles.
4. A boiler-furnace having a chimney, an

outlet-passage for the products of combustion in communication with the chimney through the flues of the boiler, a partitioned pocket in said passage to receive the products as they discharge from the flues of the boiler, one chamber of said pocket being in direct communication with the boiler-flues, a burner in the other chamber of the pocket, and baffles or dampers governing the outlet of the products from the first-named chamber of the pocket to cause the products to pass directly from the said chamber to the chimney or indirectly to the chimney from said chamber to and through the other chamber of the pocket, so as to flow out of or into the path of the flame of said burner.

In testimony whereof I affix my signature.

RUDOLPH SIMMS.

In presence of—

GEO. HEINIOKE,
HUGH TOOMEY.
